UNITED STATES PATENT OFFICE.

OTTO G. GERNEE, OF SAN FRANCISCO, CALIFORNIA.

OFFICE INDICATOR.

Application filed August 29, 1925, Serial No. 53,437. Renewed December 10, 1926.

This invention has reference to an indicator for use in business offices, and more particularly of advantage in the waiting rooms of doctors, lawyers and dentists, and 5 has for its object, broadly, to provide an indicator adapted to be used as a substitute for and to avoid the expense of a waiting room attendant or usher.

The invention includes a casing provided 10 with announcement plates and other visible and audible indicating devices to thereby facilitate the transaction of business when placed in the waiting room, the proprietor being remote therefrom.

15 The invention consists of the novel and useful construction, combination and arrangement of parts as described herein and claimed and as illustrated in the accompanying drawing, it being understood that 20 changes in form, size, proportion and minor details may be made as found to be of advantage, said changes being determined by the scope of the invention as claimed.

In the drawings, Fig. 1 is a front view 25 of an office indicator embodying my invention. Fig. 2 is a view of the same in longitudinal section, on line 2—2 of Fig. 1. Fig. 3 is a side view of an announcement plate. Fig. 4 is a side view of an obscuring plate. Fig. 5 is a view illustrating electrical circuits.

Referring now to the drawing for a more particular description, I provide a casing 1 which, for the most part, is open at its 35 front. Numeral 2 indicates the name-plate of the proprietor, said plate being secured in a stationary position near the top of the casing at the front thereof; and preferably opening on the top of the casing, below the 40 cover 37 and rearwardly of the name-plate are slots 3 and 4 adapted to receive announcement plates 3' and 4' which are provided with handles 5.

The plates thus mentioned may be constructed of any suitable material, and the plates 3' and 4' are arranged to be interchanged, that is to say,—the proprietor, when leaving his office may move the hands of the dial 6 of the plate 3' to indicate the 50 hour of his expected return. In addition to the dial, this plate bears the words "Will return", and since this plate is disposed in the slot 3, at the front, it may be seen by any client or clients who may visit this room 55 in his absence.

Upon returning to his office, the proprie-

tor may remove the plate 3' from its slot and may place the announcement plate 4' in the slot 3, the plate 3' being inserted in the slot 4. The plate 4 is used in combination with the name-plate 2 and bears the words "Is in, please ring"; and the proprietor may then leave the waiting room and enter his private office.

Below the parts last mentioned are indicated upright slots 7, these being formed in the sides of the casing, each slot 7 having an upper recess 8 and a lower recess 9 opening thereon. At 10 is indicated an obscuring-plate provided at its ends with 60 handles 11, and this plate, by use of the handles which may be disposed in the slots 7 and project outwardly of the sides of the casing, may have sliding movements upwardly or downwardly and the handles may 65 enter either pair of recesses 8 or 9, defining the upper lower position for said plate. A lamp 12 is provided in the casing and is disposed in planes midway between and 70 rearwardly of the slots 7.

At 13 is indicated a transparent announcement plate bearing the words "Mr. Brown may be delayed but expects to be back as near time indicated as possible", this plate being stationary in the casing near the 85 front of the recess 8; and at 14 is indicated a transparent announcement plate which is stationary in the casing at or near the front of the recess 9, bearing the words "Next please. Mr. Brown will see you. 90 Please step in".

Numerals 15 indicate translucent plates which are disposed at the front of the plates 13 and 14 and which normally obscure from view the lettering on the transparent plates 95 13 and 14, but permit the lettering on said plates to be seen while the lamp 12 is illuminated and, as is obvious, the plate 10 may be shifted for preventing rays of light from the lamp 12 to be directed to one of 100 the plates 13 or 14, the other plate being exposed to the light from said lamp.

Numeral 16 indicates a transparent announcement plate bearing the words "Mr. Brown is busy and will wait on you directly. Please be seated." This plate is disposed stationary in the casing and may be illuminated by a lamp 18, a translucent plate 17 being disposed at the front of the plate 16 so that the words thereon will not 110 be visible except when the lamp 18 is illuminated; and when this plate is in use

2
by illuminating the lamp 18, the lamp 12 is not illuminated, and the words on plates 13 and 14 will not be visible.

Numeral 19 indicates a push-button which is mounted in the casing for the use of clients to actuate an electrical alarm or buzzer 20; and if desired, the push-button may be excluded from view by use of members 21.

10 Numeral 22 indicates an announcement plate which is removably disposed in a slot 23 at or near the bottom of the casing, and this plate may be removed, if desired, and other announcement plates may be substituted therefor, and I may change the words on the plates 13, 14 and 16, and do not wish to be limited in this respect.

15 At 24 is indicated an electrical alarm element or buzzer adapted to be actuated by the proprietor while in his private office, and electrically connected therewith are signal elements or incandescent lamps 25, these preferably being mounted upon the sides of the casing; and in operation, the push-button 27 may be used by the proprietor to cause illumination of lamp 12 and actuation of the buzzer 24 and illumination of the lamps 25 coincident therewith to attract attention of clients in the waiting room to one of the announcement plates 13 or 14, and the proprietor may terminate electrical actuation.

20 Also by use of push-button 28 the operator may cause coincident illumination of the lamps 18 and 25 and actuation of the buzzer 24, thereby calling attention to the words of announcement of the plate 16, and may terminate the same, this announcement plate 16 being used by the proprietor while in his private office and does not wish to be interrupted or, perhaps, while otherwise engaged.

25 As described, operation will be readily understood. It will be seen that a proprietor may depend upon the indicator as a substitute for a waiting-room attendant and may remain, for the most part, in his private office. The indicator may announce to a client entering the waiting room that the proprietor is in. The client may, by use of the push-button 19, cause actuation of the buzzer 20, and being disengaged, the proprietor by use of the push-button 27 may actuate the buzzer 24 and illuminate the lamps 12 and 25, the obscuring-plate 10 being in its upper position so that only the words on the plate 14 may be seen, inviting client into the private office; and thereafter, if other clients enter the waiting room or cause actuation of the buzzer 20 while he is engaged, the proprietor, by use of the push-button 28 may give information that he is busy and requesting the client or clients to be seated, and as soon as disengaged may invite another client to enter his private office, using the push-button 27 for this pur-

pose, the illumination of the lamp 12 permitting the words on the plate 14 to be seen, the words "Next please" on said plate being understood to mean a senior client or one who has been in longer or longest waiting. 70

The lettering on plate 13 may be arranged to be visible to suit emergency cases, and of course is not used so often as the plate 14.

It will be appreciated that the electrical buzzer 24 and lamps 25 are important in 75 operation since these signals call attention to the announcement plates 13, 14 and 16. Any suitable electrical connection may be made for operating the buzzer 24 and incandescent lamps to effect a desirable result, and 80 any source of electrical energy may be employed, an electrical battery 26 being shown for this purpose.

Numeral 36 (Fig. 2) indicates an electrical conductor in communication with the electrical conductors 33, 32 and 35. 85

As best shown in Fig. 5, the buzzer 20 may be actuated by control of the switch 19 since the electrical conductor 29 communicates with one pole of the battery, and an electrical conductor 30 communicates with the opposite pole. 90

Also the switch 27 may be closed to complete an electrical circuit for coincident actuation of the buzzer 24 and illumination of 95 the lamps 12 and 25, the electrical conductors 32, 29 and 31 being in communication with one pole of the battery, and the electrical conductors 33, 34 and 30 communicating with the opposite pole. Also if the electrical switch 28 is closed an electrical circuit will be established for coincident actuation of the buzzer 24 and illumination of the lamps 18 and 25, the electrical conductors 35, 29, 31 and 33 being in communication with 100 one pole, and the electrical conductors 34 and 30 being in electrical communication with the opposite pole of the electrical battery. 105

In order that operation may be effective, the casing, preferably is of rectangular form 110 in plan and cross-section, and certain partitions are used to provide compartments 38 and 39 therein, for controlling direction of the rays of light of the lamps 12 and 18. 115

I claim as my invention,—

An office indicator comprising a casing having upright slots in its sides and having an upper and a lower recess opening on each slot, announcement-plates stationary within the casing at the front of said recesses; an incandescent lamp for illuminating said plates, and an obscuring-plate in the casing having handles traversing the slots and adapted to be moved for disposing its handles in selected recesses of the slots to prevent direction of rays of light to one of said announcement plates. 120 125

In testimony whereof, I have affixed my signature.

OTTO G. GERNER.
